DESIGN FOR A CAP FOR ELECTRICAL VAPORIZERS

Joseph Robinson, New York, N. Y.

Application October 26, 1935, Serial No. 59,234

Term of patent 7 years

To all whom it may concern:

Be it known that I, Joseph Robinson, a citizen of the United States, residing at New York, in the county of New York and State of New York, have invented a new, original, and ornamental Design for a Cap for Electrical Vaporizers, of which the following is a specification, reference being had to the accompanying drawing, forming a part thereof, in which—

Figure 1 is a side elevational view;
Figure 2 is a top plan view; and
Figure 3 is a bottom plan view of a cap for
electrical vaporizers showing my new design.

I claim:
The ornamental design for a cap for electrical
vaporizers as shown.

JOSEPH ROBINSON.
